UNITED STATES PATENT OFFICE.

JAMES G. PENNYCUICK, OF TORONTO, CANADA.

DESIGN FOR A PRISM-PLATE.

SPECIFICATION forming part of Design No. 27,341, dated July 13, 1897.

Application filed June 15, 1897. Serial No. 640,928. Term of patent 14 years.

To all whom it may concern:

Be it known that I, JAMES G. PENNYCUICK, a citizen of the Dominion of Canada, residing at Toronto, in the county of York and Province of Ontario, Canada, have invented and produced a certain new and useful Design for Prism-Plates, of which the following is a description.

My invention relates to designs for prism-plates.

It is illustrated in the accompanying drawings, wherein—

Figure 1 is an elevation of a prism-plate, looking toward the prism side. Fig. 2 is a section therethrough.

Like parts are indicated by the same letter in all the figures.

A is a surrounding frame; B B and C C, the parts which form the inner net, grid, or frame.

The prism-lights D D are composed each of

a body with prisms E E thereon. These prism-lights are substantially square or rectangular, and the prisms are arranged thereon substantially as indicated, being practically horizontal to the transverse or horizontal axes of the 25 prism-light.

I have shown a certain size and arrangement of the several parts and of the prisms on the light; but the essential feature of my invention is a single complete plate composed 30 of prism-lights with diagonally-arranged inner frame-pieces, the prisms placed horizontally.

I claim—

The design for a prism-plate substantially 35 as shown and described.

JAMES G. PENNYCUICK.
